US0D1074077S

(12) **United States Design Patent** (10) **Patent No.:** **US D1,074,077 S**
(45) **Date of Patent:** **** May 6, 2025**

(54) **BIRD FEEDER**

(71) Applicant: **Jie Chen**, Ningbo (CN)

(72) Inventor: **Jie Chen**, Ningbo (CN)

(**) Term: **15 Years**

(21) Appl. No.: **29/945,515**

(22) Filed: **Jun. 4, 2024**

(51) LOC (15) Cl. **30-03**

(52) U.S. Cl.

USPC **D30/124**

(58) **Field of Classification Search**
